TELEVISION ANTENNA COUPLER

Robert D. Kahn, Rockville Centre, N.Y., assignor to
Fedtro, Inc., Rockville Centre, N.Y., a corporation of
New York

Filed Apr. 25, 1969, Ser. No. 16,907

Term of patent 14 years

Int. Cl. D14—03

U.S. Cl. D26—14

FIG. 1

FIG. 2

FIGURE 1 is a front perspective view of the television antenna coupler; and

FIGURE 2 is a rear perspective view thereof.

The right side view of the television antenna coupler is a mirror image of the left side.

I claim:

The ornamental design for a television antenna coupler, as shown and described.
